UNITED STATES PATENT OFFICE.

WILLIAM E. TOLER, OF PAWNEE, OKLAHOMA.

ATTACHMENT FOR THRASHING MACHINES AND CLOVER HULLERS.

Application filed May 29, 1922. Serial No. 564,446.

To all whom it may concern:

Be it known that WILLIAM E. TOLER, a citizen of the United States of America, residing at Pawnee, in the county of Pawnee and State of Oklahoma, has invented certain new and useful Improvements in Attachments for Thrashing Machines and Clover Hullers, of which the following is a specification.

10 This invention relates to an improved system of handling straw, chaff, tailings and refuse for thrashing separators or machines, clover hullers, and other like machinery.

The principal object of the above entitled 15 invention is to provide in a single machine a mechanism which will reduce to a minimum the power usually required by larger machines doing the same work by the reduction of friction due to the elimination 20 of a number of bearings, drive belts and other mechanical parts usually associated with such machines.

A further feature is the production of a 25 machine designed to more thoroughly clean out and thresh the material and to increase the capacity or output of the machine without a corresponding increase in the size of the machine, and with the use of a smaller and less powerful power plant.

30 Other objects and advantages will appear to those familiar with the art to which this invention relates.

In the accompanying drawings,

35 Figure 1 is a side elevation of the right hand side of a thresher showing the straw and chaff elevator and a portion of the stacker tube in section;

40 Figure 2 is a view similar to Figure 1, but illustrating certain of the other conveyor tubes;

Figure 3 is a side elevation of the left hand side of a thresher showing the arrangement of the tailings elevator tube;

45 Figure 4 is also a side elevation of the left hand side of the thresher but showing the blower, air conducting tube and cleaning riddles;

50 Figure 5 is a transverse section thru the separator at the forward end thereof and illustrating the thrashing cylinder and the blower and suction fan chambers.

Figure 6 is a transverse vertical sectional view thru the separator and the air chamber,

55 Figure 7 is a transverse vertical sectional

view thru the separator adjacent the rear thereof and showing the feeder, and

Figure 8 is a transverse vertical sectional view thru the thresher showing the grain separator such as illustrated in Figure 2 60 of my prior Patent 1,392,094, dated Sept. 27th, 1921.

Referring to the drawings by numerals of reference, wherein the characters denote like parts thruout the several figures, 2 indicates 65 the frame of the machine, which may be of the usual character in general construction and design.

Arranged transversely within the machine, near the forward portion thereof, on 70 a shaft 4 is a thrashing cylinder 5, said shaft being provided upon each side of the machine with lateral extensions 6 and 8 to which may be keyed or otherwise fixed one or more pulleys 10 whereby the apparatus may be driven by suitable driving belts with the power plant not necessary 75 to be shown.

Arranged within a casing 12 suitably mounted to one side of the machine, is a 80 blower fan 14, having a lateral air inlet tube 15 communicating therewith, and provided at its lower end with an outlet communicating with a downwardly and rearwardly inclined air tube 16, at the bottom 85 of which is connected an air chamber 18 disposed transversely of said machine.

The air is delivered from the air chamber 18 thru a series of passageways 19 into a series of vertically arranged riddles 20 which, 90 thru a tube 22 open into a chamber 24, containing a feed screw 25 arranged transversely of the machine near the rear portion thereof. The chaff and straw from the feed-screw 25 is delivered into a tube 26

95 which is in communication with a suction fan 28 within a fan chamber 29. Extending transversely through the frame 2 is the tubular chamber 30, the latter being provided with a series of spaced openings 50 in the bottom thereof for the purpose of providing means whereby the suction in the chamber will lift the chaff from the grain through the openings. The chaff thus lifted from the grain will tend to lighten the load and the chaff is then conveyed through the chamber 30 and the pipe 44 connected thereto to the stacker of the separator. The suction further, draws the straw thru the pipe or tube 26 from the feeder 25, where it isulti-

100

110

mately delivered thru an air pipe 32 to the stacker pipe 34.

In Figure 1 of the drawings, I have shown an air and straw deflector 35 which deflects the air and straw downwardly during its movement onto a grain saving device 36 which catches and retains a considerable quantity of kernels of grain heretofore lost.

Referring again to Figure 5, I have shown 10 arranged on the shaft 6, and with the chamber or casing 12, but separated by a partition 38 from the blower chamber, a suction fan 40, to which is delivered thru an inclined conduit 41, which may be termed a tailings 15 elevator tube, air and tailings, which are delivered thru a tube 42 to the separator.

In Figure 2, 28 indicates the suction fan as shown in Figure 5 and is designed to perform the same character of work, although 20 the straw is not carried thru the pipe 44 to said fan 28, but by taking up the air and chaff from 30 carries the same by pipe 44 to said fan 28, from whence it is delivered by a tube 45 to the stacker tube 46, picking 25 up the straw from the feeder 48 delivered by the feed screw 25.

What I claim as new and desire to protect by Letters Patent is:

1. In an apparatus of the class described, 30 a thrashing cylinder, a blower mounted on the shaft thereof, a series of riddles adapted

to receive air from said blower, a tailings elevator, in communication with said riddles, a suction fan for said tailings elevator, on said thrashing cylinder shaft, a straw and chaff elevator tube, a suction fan for said tube on the thrashing cylinder shaft and a straw stacker tube in communication with said last named suction fan said fan being adapted to deliver straw to said stacker tube.

2. In an apparatus of the class described, a thrashing machine frame, a thrashing cylinder journaled within said frame, a pair of suction fans arranged on opposite sides of said machine frame and on said thrashing cylinder shaft, a blower also arranged on said shaft, a casing surrounding said blower and one of said fans, a partition separating said blower and said suction fan, a riddle chamber containing a series of riddles, an air chamber communicating with said riddle chamber, an air tube leading from said blower to said air chamber, means of communication between said blower and one of said suction fans embodying a straw and chaff elevating tube communicating with the other of said suction fans, a stacker tube, and a tube leading from said last named suction fan to said stacker tube.

In testimony whereof I affix my signature.

WILLIAM E. TOLER.
